CLAIM

The ornamental design for a fishing reel, as shown and described.

DESCRIPTION

FIG. 1 is a first perspective view of a fishing reel in accordance with our new design;

FIG. 2 is a second perspective view of the fishing reel illustrated in FIG. 1;

FIG. 3 is a first side elevational view of the fishing reel illustrated in FIG. 1;

FIG. 4 is a second side elevational view of the fishing reel illustrated in FIG. 1;

FIG. 5 is a top plan view of the fishing reel illustrated in FIG. 1;

FIG. 6 is a bottom plan view of the fishing reel illustrated in FIG. 1;

FIG. 7 is a first end elevational view of the fishing reel illustrated in FIG. 1;

FIG. 8 is a second end elevational view of the fishing reel illustrated in FIG. 1;

FIG. 9 is another perspective view of the fishing reel illustrated in FIG. 1, but with an operating part being moved to an alternate position;

FIG. 10 is still yet another perspective view of the fishing reel illustrated in FIG. 1, but with the operating part being moved to the alternate position as illustrated in FIG. 9; and,

FIG. 11 is a side elevational view, similar to FIG. 3, of the fishing reel illustrated in FIG. 1, but with the operating part being moved to the alternate position as illustrated in FIGS. 9 and 10.
